UNITED STATES PATENT OFFICE.

VIRGIL T. GRABS, OF KING, NORTH CAROLINA.

LOG-TURNING DEVICE.

973,423.

Specification of Letters Patent. Patented Oct. 18, 1910.

Application filed April 15, 1910. Serial No. 555,641.

To all whom it may concern:

Be it known that I, VIRGIL T. GRABS, a citizen of the United States, residing at King, in the county of Stokes and State of North Carolina, have invented new and useful Improvements in Log-Turning Devices, of which the following is a specification.

This invention relates to a log turning device for saw mills, the object of the invention being to provide a device of this character which is simple of construction, operative to positively turn the logs, and adapted to be conveniently thrown out of operation when its use is not desired.

15 The invention consists of the features of construction, combination and arrangement of parts hereinafter fully described and claimed, reference being had to the accompanying drawings, in which:—

20 Figure 1 is a top plan view of a portion of a saw mill frame embodying my invention. Fig. 2 is a vertical transverse section on the line 2—2 of Fig. 1, showing a log in the operation of being turned. Fig. 3 is a view 25 similar to Fig. 1, showing a modification in the construction of the log turner. Fig. 4 is a vertical transverse section on the line 4—4 of Fig. 3.

Referring particularly to Figs. 1 and 2 of the drawings, 1 designates a saw mill frame, 2 the carriage mounted to travel thereon, and 3 the adjustable knees or abutments against which the rear side of the supported log 4 rests. Journaled in the frame 1 is a 35 transverse drive shaft 5 carrying a pulley 6 for receiving power from a suitable source, and provided at its front and rear ends with bevel gears 7 and 8. The gear 7 meshes with a gear 9 on a transmission shaft 10 journaled longitudinally in bearings at the front of the frame and carrying a spur gear 11. Arranged above the shaft 10 is a rock shaft 12 carrying a loose idler gear 13 meshing with the gear 11 and provided with bracket 40 arms 14 forming bearing supports for a swinging shaft 15, carrying a gear 16 meshing with the idler gear 13, whereby said shaft is driven and also carrying smooth-surfaced log-turning rolls 17. A lever 18 is 45 connected with the shaft 12, whereby the latter may be rocked to swing the shaft 15 toward or from the front of the carriage. By such movement of the shaft 15 the rolls 17 may be brought into contact with the front 50 portion of the log below its center or swung to the dotted line position shown in Fig. 2

out of engagement with said log. The rolls are revolved inwardly and rearwardly by the gearing, as indicated by the arrows in Fig. 2. Upon the rear of the frame 1 are 55 arranged upwardly extending spaced bracket arms 19 in the lower and upper ends of which are respectively journaled shafts 20 and 21. The lower shaft 20 is provided at one end with a beveled gear 22 meshing with the gear 8 and drives the upper shaft 21 through sprocket gearing 23.

Pivottally connected at its rear end to the shaft 21 is a transverse swinging bracket 24 having front and rear forked ends, said 70 bracket being adapted to be swung upwardly and rearwardly to an inoperative position or downwardly and forwardly over the carriage to an operative position. The free forward end of this bracket carries a sprocket 75 wheel 25 and is provided with a suitable manipulating handle 26, while upon the shaft 21 between the arms of the rear end of the bracket is keyed a sprocket wheel 27. Between the two sprocket wheels extends an 80 endless chain 28 having its links provided with hooked teeth or projections 29, the upper and lower stretches of the chain extending longitudinally above and below the body of the bracket. As shown, the arms of the 85 rear fork of the bracket are formed with sleeves 30 which loosely engage the shaft 21, and carried by these sleeves are weights 31 which counterbalance the weight of the bracket and the parts carried thereby, thus 90 enabling the bracket to be swung from an inoperative to an operative position, and vice versa, in an easy and convenient manner. It will be observed that the gearing drives the chain 28 so that its lower stretch 95 moves forwardly, and that the hooks 29 face in such direction of movement.

When the bracket is swung upwardly to an inoperative position, it may be balanced in such position by the counterweights 31 100 or supported in any other suitable manner.

In operation when it is desired to turn the log 4 the rolls 17 are swung upwardly into contact with the log and then the bracket is swung downward to cause the teeth 29 upon 105 the front end of the lower stretch of the chain to engage the upper rear surface of the log above its longitudinal center, the rollers 17 engaging the lower front surface of the log below its horizontal center as 110 shown in Fig. 2. As, therefore, the rollers 17 will exert a turning pressure upon the

base of the outer side of the log, while the teeth of the lower stretch of the chain will engage the upper portion of the inner surface of the log and force the same outwardly, it will be apparent that the log will be given a more or less complete turn, depending upon the duration or extent of the turning movement.

In the embodiment of my invention disclosed in Figs. 3 and 4, the turning rolls 17 and the same type of drive gearing are employed as in Figs. 1 and 2, but instead of the bracket 24 and the endless turning chain 28, a substantially U-shaped bracket 32 is employed having its arms provided with sleeves 33 which loosely engage the shaft 21 and carrying counterweights 34, the forward portion or cross bar of the bracket being provided with an operating handle 35. Extending longitudinally of said bracket in parallel relation are turning devices 36 each comprising a bar provided at its forward end with downwardly and forwardly projecting log engaging teeth 37. The rear ends of the bars are formed with sleeves 38 which engage cranks 39 arranged at an angle of 180° on the shaft 21, while the forward ends of the bars have a loose sliding and pivotal engagement with the cross bars 30 of the bracket through the medium of longitudinal guide members 40. By this construction the toothed bars are adapted to reciprocate alternately in opposite directions in an undulatory path, the toothed portion 35 of each bar being depressed on its forward motion and elevated on its rearward motion, as will be readily understood. When the bracket 32 is, therefore, swung downward to an operative position, the previously adjusted rolls 17 will engage the lower front

surface of the log, as hereinbefore described, while the toothed bars on their forward motion will alternately engage the upper rear surface of the log, whereby the latter will be turned.

45

Having described the invention, I claim:—

1. In a log turning device, the combination, with a saw-mill frame and carriage, of a drive shaft mounted upon one side of the frame and carrying a driving gear, a rock shaft arranged above said driving shaft and carrying an idler meshing with said gear, arms carried by the rock shaft, a third shaft supported by said arms and carrying a gear meshing with said idler, turning rolls supported by the third shaft, means for swinging the rock shaft to force said rolls into and out of engagement with one side of a log, a coöperating device mounted upon the opposite side of the frame to engage the opposite side of the log, and means for driving the said device and the rolls through said gearing in opposite directions.

55

2. In a log turning device, the combination, with a saw-mill frame and carriage, of turning rolls mounted upon one side of the carriage, gearing for driving said rolls, a transverse shaft for driving said gearing, a bracket pivotally mounted for movement in a vertical plane at the opposite side of the frame, a turning device carried by said bracket, and gearing driven by the transverse shaft for operating said turning device.

65

In testimony whereof I affix my signature in presence of two witnesses.

VIRGIL T. GRABS.
